UNITED STATES PATENT OFFICE.

RICHARD H. DIMOCK, JOSEPH SHEAVER, AND GEORGE WYSKOCIL, OF CEDAR RAPIDS,
IOWA.

WRENCH.

1,388,029.

Specification of Letters Patent. Patented Aug. 16, 1921.

Application filed February 10, 1921. Serial No. 443,968.

To all whom it may concern:

Be it known that we, RICHARD H. DIMOCK, JOSEPH SHEAVER, and GEORGE WYSKOCIL, citizens of the United States, residing at 5 Cedar Rapids, in the county of Linn and State of Iowa, have invented certain new and useful Improvements in Wrenches; and we do hereby declare the following to be a full, clear, and exact description of the invention, such as will enable others skilled in the art to which it appertains to make and use the same.

This invention relates to wrenches of the adjustable, angle-jaw type, and the object 15 of the invention is to produce a wrench of this type in which the adjustment of the jaws for different sized nuts is effected in a simple manner, and by the turning of the wrench handle.

20 The invention is fully set forth and claimed in the description and claims following, reference being had to the accompanying drawing, in which—

Figure 1 is a side view of the wrench, the 25 fixed jaw being shown in section. Fig. 2 is a fragmentary elevation of the wrench as seen from the left of Fig. 1. Fig. 3 is a plan view of the movable jaw, as seen from the under (handle) side. Fig. 4 is a plan view 30 of the conical scroll which engages the movable jaw. Fig. 5 shows a central section of the same, and a fragmentary section of the fixed jaw transverse thereto.

In the drawing, the numeral 5 denotes the 35 jaw which may be designated as the fixed jaw. This is mortised at 6 to receive the shank 7 of the movable jaw 8. This shank is here shown as formed with lateral, parallel ribs 9 which fit slidably in correspond- 40 ing grooves 10 of the mortise, and serve to guide the movable jaw and hold it in true working position. The depending portion of the shank, 11, is formed as a rack, having teeth 12, preferably somewhat cres- 45 cent-shaped, as shown in Fig. 3 to mesh with a spiral scroll 13 attached to the wrench-handle 14. As the handle stands at an angle to the rack of less than 90 degrees (60 degrees, as shown), the scroll is 50 formed as the frustum of a cone, and but one side of its spiral thread 13^a engages the rack. The scroll is held in such engagement by shoulders 15 of a hole 16 in the fixed jaw. At right-angles to these shoulders is a hole 55 17, preferably tapered, to give added

strength to the handle, to receive the tapered shank 18 of the handle. In practice the scroll is screwed on the threaded end 19 of the handle, and secured against unscrewing by a pin 20. The scroll is shown to project 60 a little beyond the faces of the fixed jaw, as it may do without interfering with the action of the wrench in close places, and the periphery of the scroll being milled, the handle may be turned thereby, by the use of a thumb 65 or finger.

The advantages of an angle-jaw wrench, in turning nuts in a limited space for the movement of the handle, are well-known and universally recognized. This wrench has the 70 further advantage of enabling the operator to draw the jaws up tightly on the nut by turning the handle, the action of which gives a vise-like grip on the nut. This is especially convenient and desirable in the 75 restricted spaces of automobiles and other machinery, where the operator must work practically at arms length in some cases, and with only a grasp of the wrench near the handle end.

Having thus described our invention, we 80 claim:

1. In an angle-wrench, a fixed jaw mortised to receive the rack-toothed shank of a movable jaw, a movable jaw having a shank 85 at right angles to its working face, and fitting said mortise, a handle inclined at less than ninety degrees to said shank, and provided with a conical, spiral scroll engaging said shank.

2. In an angle-wrench, a fixed jaw mortised at right angles to its working face, a movable jaw with a rack-toothed shank slid- 95 able in said mortise, a handle revolvably mounted in the fixed jaw at less than a right angle to said shank, and a conical spiral scroll attached to said handle, and engaging at one side the rack-teeth of said shank.

3. An angle-jaw wrench, comprising a 100 fixed jaw mortised to receive the shank of a parallel-faced movable jaw, and having an adjacent hole to receive a scroll, with retaining shoulders therefor, and a communicat- 105 ing hole for the shank of a handle, a movable jaw having a right-angled rack-toothed shank slidable in the mortise, a handle revolv- 110 able in the fixed jaw, and a conical scroll attached thereto, and engaging the shank of the movable jaw.

4. In an angle-jaw wrench having a fixed 110

jaw, a movable jaw slidable transversely thereof, and rack-toothed for engagement with a scroll, a handle mounted revolubly in the fixed jaw and inclined to its nut-engaging face, and a conical scroll screwed on the end of the handle, and engaging the rack-teeth at one side, the fixed jaw having a hole to receive the scroll, and shouldered to hold it in engagement with the rack.

In testimony whereof we affix our signatures in presence of two witnesses.

RICHARD H. DIMOCK.
JOSEPH SHEAVER.
GEORGE WYSKOCIL.

Witnesses:

J. M. ST. JOHN,
O. A. KEARNEY.
